TRUCK

William E. Burbank, Westfield, and Donald H. Mitchell, Cranford, N. J., assignors to Western Electric Company, Incorporated, New York, N. Y., a corporation of New York

Application January 9, 1943, Serial No. 471,848

11 Claims. (Cl. 254—10)

This invention relates to trucks and more particularly lift trucks employed in the transportation of articles.

Articles contained in trays or machinery of various sizes are frequently transported by the aid of lift trucks through the assistance of skids upon which such articles or machines are originally disposed. The skids include a platform usually of a standard size having supporting legs to locate it above the floor a suitable distance for the movement of the supporting frame of a lift truck therebeneath. In certain instances, however, articles or machines to be transported are too large for the commercially known single skid and for this reason double or larger skids are employed. However, the standard lift truck designed for the single skids is not capable of transporting the double or larger skids.

An object of the invention is to provide a truck particularly one of the lift type adapted for variation in length for the transportation of articles of various sizes.

With this and other objects in view the invention comprises a truck having a frame formed of sections movable relative to each other, operable mechanism adapted to move the sections to vary the length of the frame for the supporting of articles of various sizes thereon.

Other objects and advantages will be apparent from the following detailed descriptions when considered in conjunction with the accompanying drawings, wherein

Fig. 1 is a side elevational view of the truck illustrating the frame portions extended, portions of these frames being illustrated in Fig. 2;

Fig. 2 is a continuation of the structure shown in Fig. 1;

Fig. 3 is a fragmentary top plan view of the truck with the frame sections extended;

Fig. 4 is a fragmentary side elevational view of the truck with frame sections in their normal positions;

Fig. 5 is an enlarged fragmentary sectional view taken along the line 5—5 of Fig. 3;

Fig. 6 is an enlarged fragmentary sectional view illustrating a portion of the operating means for the frames, and

Fig. 7 is a perspective view of one of the intermediate members connecting the sections of the frames for their movement relative to each other.

Referring now to the drawings, attention is first directed to Fig. 1 which illustrates a lift truck, indicated generally at 10, mounted upon wheels 11 and provided with conventional mechanism, for propelling and guiding the truck, such

mechanism, not constituting a part of this invention. A main frame indicated generally at 14 is supported by the wheels 11 and is composed mainly of two sections 15 and 16. The section 15 is fixed to the propelling portion of the truck, the members of this section extending forwardly in spaced parallel relation as illustrated in Fig. 3. The parallel members of the section 15 have dovetail slots 18 formed longitudinally in the outer surfaces thereof as shown in Figs. 1 and 5. The section 16 is substantially U-shaped in general contour, the leg portions of which have dovetail slots 19 in the inner surfaces thereof. A pair of connecting members 20, one a right hand member as shown in Fig. 7 and the other a left hand member with the dovetail projections on the opposite sides, is employed for the connection of the sections 15 and 16 through their dovetail slots 18 and 19. The connecting member 20 illustrated in Fig. 7 has a central portion 22 of a given width and length with dovetail projections 23 and 24 mounted upon their respective sides and at the positions shown substantially overlapping each other for portions of their lengths adjacent the center of the member 20. The dovetail portions 23 and 24 of the connecting members 20 are receivable in their slots 18 and 19, respectively, to thus positively connect the sections for relative movement to cause variation in the length of the frame. Attention at this time is directed to the central portion 22 of connecting members, this portion having a projection or an increased width for a portion of its length to provide an abutment 26 for a purpose hereinafter described.

A lifting frame indicated generally at 28 is similar in structure to the main frame 14, it being composed of two sections 29 and 30 having dovetail slots 31 and 32, respectively, therein, the slots 31 being in the outer surfaces of the section 29 while the slots 32 are disposed in the inner surfaces of the section 30. Right and left hand connecting members 33 identical in structure to the connecting members 20 with the addition of integral lugs 34, have dovetail members 35 and 36 disposed in their respective slots 31 and 32 (Fig. 5) to connect the sections 29 and 30 for movement relative to each other. The frame 28 is provided with a platform for supporting articles to be transported by the truck. Due to the possible variations in the size of the frame 28 this platform must of necessity be formed in portions or sections so as to distribute supporting portions throughout the length of the frames when extended. A main portion indicated at 38

is mounted upon the frame section 29, this portion having a vertical flange 38 serving as a stop in locating articles upon the truck. An intermediate portion 40 has apertures 41 at the sides thereof for receiving the lugs 34 of the connecting members 33 and through these lugs become fixed to the connecting members. A final or end portion of the platform indicated at 42 is mounted upon the section 30 of the lift frame 28.

The operable means for varying the size of the frames for moving them from the normal positions of the sections shown in Fig. 4 to the extended positions shown in Figs. 1, 2 and 3, or to any intermediate positions includes sets of chains 45 and 46. The chains 45 each have one of their ends connected to integral lugs 41 of an element 48 which extends horizontally beneath the section 15 of the frame 14 and is secured in recesses 50 of the section 16 by suitable means such as screws 51 (Fig. 5). The connection between the chains 45 and their lugs 41 consists of bolts 52 constituting means to vary the tensions of the chains and/or their locations with respect to their sprockets. Extending from the lugs 41, the chains 45 pass around their respective sprockets 53, which are mounted upon a common shaft 54, up and around their respective sprockets 55, which are mounted on a common shaft 56, then extend longitudinally of the frame 28 to their respective sprockets 57 about which they pass to their respective sprockets 58 and finally have their opposite ends connected through the aid of adjustable bolts 60 to other lugs 61 of the member 48. The sprockets 57 are mounted upon a common shaft 62 and the sprocket wheels 59 are mounted upon a common shaft 63. The shafts 54, 56, 62 and 63 are suitably journaled in bearings mounted in their respective frame sections. Therefore the links 68 and 69, employed with other mechanism 65 for lifting the frame 28, have their ends pivotally mounted upon their respective shafts.

The chains 46 extend from lugs 70 of an element 71 substantially identical in structure to the element 48, the connecting means between the ends of the chains 46 and the lugs 70 constituting adjustable bolts 72. The chains 46 extend from their bolts 70 about sprockets 73, then longitudinally of the frame 28 where they extend about sprockets 75 and finally have their opposite ends connected at 76 to lugs 77 of the element 71. The sprockets 73 are fixed to the shaft 56 and are driven thereby, the sprockets 75 being fixed to the shaft 62 to rotate therewith. The element 71 is positioned to engage abutments 78 (Fig. 4) of their respective members 33 and has its ends fixed in recesses 80 (Figs. 4 and 5) of the section 30 by suitable means such as screws 81.

The means to operate the mechanism including the chains and sprockets for varying the length of the frames includes a reversible motor 83 mounted upon a suitable support 84 and including a speed reducing unit 85, the output shaft 86 of which is operatively connected to the shaft 54 through the aid of bevelled gears 87 and 88. The electrical circuit for controlling the motor is not shown, it being understood that such a circuit may be provided to cause energization of the motor when desired.

Considering now the operation of the truck, particularly the variation in the size of the frames, let it be assumed that the frames are in the normal or closed positions shown in Fig. 4 and that the operator is desirous of extending

the lengths of the frames to effectively lengthen the supporting area of the truck. The motor 83 is then energized, causing rotation of the shaft 54 counterclockwise (Fig. 4) imparting movement to the pairs of chains 45 and, through their driving connections with the shafts 56 and 62 causing simultaneous movements of the chains 46 to cause movement of their members 48 and 71 simultaneously to the right, moving with them their respective sections 16 and 30 relative to their sections 14 and 29. The connecting members 20 and 33 with their dovetail portions in the dovetail slots of the frame sections permit this movement, maintaining a sufficiently rigid structure regardless of the extended length of the frames. This operation may be continued, if desired, to move the frame sections 16 and 30 their complete distances. It will be noted by viewing Fig. 4 that the abutments 28 and 79 of the members 20 and 33 are spaced from the elements 48 and 71 at the start of this adjustment. However, the abutments are in the path of their respective elements 48 and 71 and will be moved thereby to equalize the connections of the members 20 and 33 with respect to their frame sections. Thus at the end of the adjustment of the frame sections the effective length of the frames will be substantially doubled, as illustrated by comparing Figs. 3 and 4. During this adjustment or elongation of the frames, the portions 40 and 42 of the platform are moved away from each other and from the portion 38 so that there will be platform portions for the extended frames. The portion 42 is moved with the frame section 30. The portion 40 remains adjacent the portion 38 of the platform until the members 33 are moved by the element 71, then it assumes a position substantially midway between the portions 38 and 42.

40 The shortening of the frames is brought about in substantially the reverse order, the motor 83 being of the reversible type may cause rotation of the shaft 54 in a clockwise direction to cause movement of the members 48 and 71 simultaneously in directions toward the motor to pull their respective sections 16 and 30, to which they are secured, into their closed positions. During a portion of this movement the connecting members 20 and 33 will remain at rest, maintaining their connections between the frame sections and will finally be moved through the ends of the slots 19 and 32 engaging their respective portions 24 and 36 or in one instance through the abutment of the platform portion 42 with the portion 40, causing movement of the latter into engagement with the portion 38 during which time the members 20 and 33 are returned to their normal positions.

Although specific improvements of the invention have been shown and described it will be understood that they are but illustrative and that various modifications may be made therein without departing from the scope and spirit of this invention as defined by the appended claims.

60 What is claimed is:

1. A truck for transporting articles comprising a main frame having relatively movable sections, a lift frame having relatively movable sections, shafts rotatably supported by the frames, lifting means pivotally mounted upon the shafts to cause movement of the lifting frame toward and away from the main frame, endless members operatively connected to the shafts and driven by one of them, and means respectively movable by the

endless members to cause relative movement of the sections of their respective frames.

2. A truck for transporting articles comprising a main frame having relatively movable sections, a lift frame having relatively movable sections, shafts rotatably supported by the frames, lifting means pivotally mounted upon the shafts to cause movement of the lifting frame toward and away from the main frame, endless members operatively connected to the shafts and driven by one of them, and means respectively movable by the endless members to cause relative movement of the sections of their respective frames and means to rotate the driven shaft to cause movement of the endless members.

3. A truck for transporting articles comprising a main frame having relatively movable sections, a lift frame having relatively movable sections, shafts rotatably supported by the frames, lifting means pivotally mounted upon the shafts to cause movement of the lifting frame toward and away from the main frame, endless members operatively connected to the shafts and driven by one of them, and means respectively movable by the endless members to cause relative movement of the sections of their respective frames and means to rotate the driven shaft in either direction to cause movement of the endless members in either direction.

4. A truck for transporting articles comprising a main frame having relatively movable sections, a lift frame having relatively movable sections, means, connecting the frames, actuatable to cause movement of the lift frame relative to the main frame, and means operatively connected and operable in synchronism to simultaneously cause relative movement of the sections of the frames.

5. A truck for transporting articles comprising a main frame having relatively movable sections, a lift frame having relatively movable sections, means, connecting the frames, actuatable to cause movement of the lift frame relative to the main frame, and means connected to both frames and operable to cause relative movement of the sections of the frames when the lifting frame is in a position away from the main frame.

6. A truck for transporting articles comprising a main frame having relatively movable sections, a lift frame having relatively movable sections, means, connecting the frames, actuatable to cause movement of the lift frame relative to the main frame, and means connected to both frames and operable to cause relative movement of the sections of the frames when the lifting

frame is in any of its positions relative to the main frame.

7. A truck for transporting articles comprising a main frame having relatively movable sections, a lift frame having relatively movable sections, means, connecting the frames, actuatable to cause movement of the lift frame relative to the main frame, and means connected to both frames and operable to cause relative movement of the sections of the frames during movements of the lifting frame relative to the main frame.

8. A truck for transporting articles comprising a main frame having relatively movable sections, a lift frame having relatively movable sections, means, connecting the frames, actuatable to cause movement of the lift frame relative to the main frame, means connected to both frames and operable to cause relative movement of the sections of the frames when the lifting frame is in any of its positions relative to the main frame, and power means to operate the said operable means.

9. A truck for transporting articles comprising a main frame having relatively movable sections, a lift frame having relatively movable sections, means, connecting the frames, actuatable to cause movement of the lift frame relative to the main frame, separate connecting members between the sections of the frames to maintain connections therebetween during their relative movements, and means operatively connected to both frames to cause relative movement of the sections of the frames simultaneously.

10. A truck for transporting articles comprising a main frame having relatively movable sections, a lift frame having relatively movable sections, means, connecting the frames, actuatable to cause movement of the lift frame relative to the main frame, endless moving members for the frames, and means movable with the members to cause relative movement of the sections of the frames.

11. A truck for transporting articles comprising a main frame having relatively movable sections, a lift frame having relatively movable sections, means, connecting the frames, actuatable to cause movement of the lift frame relative to the main frame, operable endless members for the frames, means movable through the operation of the members to cause relative movement of the sections of the frame, and means to cause operation of the members.
